SUCTION CLEANER OR SIMILAR ARTICLE

Raoul A. Lambert, Springfield, Mass., assignor to Westinghouse Electric Corporation, a corporation of Pennsylvania

Application February 23, 1954, Serial No. 29,144

Term of patent 14 years

(Cl. D9—2)

To all whom it may concern:

Be it known that I, Raoul A. Lambert, a citizen of the United States, residing at Springfield, in the county of Hampden and State of Massachusetts, have invented a new, original, and ornamental Design for a Suction Cleaner or Similar Article, of which the following is a specification, reference being had to the accompanying drawing, forming a part thereof.

Fig. 1 is a perspective view of a suction cleaner or similar article embodying my new design; and

Fig. 2 is a perspective view of the suction cleaner or similar article turned around from the position shown in Fig. 1, to show the opposite side and end.

The essential features of the design are shown in full lines.

I claim:

The ornamental design for a suction cleaner or similar article, substantially as shown and described.
